HYDRAULIC LET-OFF

Archibald J. Herard, Jr., Worcester, Mass., assignor to Crompton & Knowles Loom Works, Worcester, Mass., a corporation of Massachusetts

Application October 13, 1941, Serial No. 414,729

10 Claims. (Cl. 139—109)

This invention relates to let-off mechanisms for looms and it is the general object of the invention to provide a let-off controlled hydraulically by tension of the warp threads.

In certain types of let-off mechanisms it is customary to employ a whip roll which is moved forwardly by the tension of the warp during the weaving operation and while the warp beam is held stationary. When the whip roll reaches a given forward position mechanism is operated to release the warp beam so that it can be turned by the warp to reduce tension and permit the whip roll to move rearwardly under the action of a weight or spring. When the whip roll reaches a critical rearward position the warp beam is again locked, and the alternate locking and unlocking of the beam by back and forth motion of the whip roll goes on throughout the weaving operation to supply the warp under proper tension as needed.

It is an important object of my present invention to provide a hydraulic system for controlling the warp beam together with means for acting on the system by mechanism dependent for its operation upon a part, such as a whip roll, the position of which is changed by the warp. My invention contemplates the use of brake shoes operated by a hydraulic unit connected to a hydraulic cylinder the plunger of which is controlled by the part to hold and release the beam alternately during loom operation. The system normally tends to cause the brake shoes to hold the warp beam stationary, and as the whip roll moves forwardly the pressure within the system is gradually reduced until the brake shoes slacken enough to permit the warp beam to turn. During the consequent slackening of the warp threads the whip roll moves rearwardly under action of the weight and acts on the cylinder plunger to return the shoes to locking position. In the description to follow I have illustrated a single system applied to but one end of the loom, but I am not limited to such an application, as it is obvious that the mechanism can be duplicated at the opposite end.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a rear elevation of one end of a loom having my invention applied thereto,

Fig. 2 is a plan view taken in the direction of arrow 2, Fig. 1 and showing the hydraulic sys-

tem under control of both ends of the whip roll,

Fig. 3 is a side elevation taken in the direction of arrow 3, Fig. 2,

Figs. 4, 5 and 6 are vertical detail sections on lines 4—4, 5—5 and 6—6, respectively, of Fig. 1,

Fig. 7 is a vertical longitudinal section on line 7—7 of Fig. 3,

Fig. 8 is a detailed vertical section through the hydraulic cylinder on line 8—8, Fig. 2, on an enlarged scale, and

Fig. 9 is a vertical section through the brake operating hydraulic unit shown in elevation in Fig. 6.

Referring particularly to Figs. 1, 2 and 3, I have shown a loom frame 10, warp beam 11 and whip roll 12 of the usual construction. A bracket 13 secured to the loom frame extends rearwardly and has pivoted thereto as at 14 an upwardly extending arm 15 on which the adjacent end of the whip roll is journaled as at 16. The warp W from the warp beam is led upwardly and over the whip roll and then forwardly to the point of weaving.

A lever 20 swinging in a vertical plane is pivoted as at 21 on the bracket 13 and has a horizontal arm to support a weight rod 22 the lower end of which carries weights 23. As shown particularly in Fig. 2 a control lever 25 swinging in a horizontal plane is pivoted as at 26 to the bracket and has a lateral arm 27 to engage the front edge of the adjacent arm 15. Lever 25 also has a forwardly extending arm 28 pivoted as at 29 to a link 30 which in turn is pivoted to a second link 31 the right end of which is shown in Fig. 1 as pivoted at 32 to a part of lever 20 above the pivot 21. A rod 33 connected to link 30 in the present instance is shown in Fig. 2 as extending across the loom to be connected to a second control lever 35 similar to lever 25 to engage an arm 36 similar to arm 15 on which the left end of the whip roll is journaled.

In the mechanism thus far described, and assuming for the moment that the warp beam is stationary, the whip roll 12 will move forwardly to swing the arms 15 and 36 toward the front of the loom and effect a left hand angular motion of levers 25 and 35 as viewed in Fig. 2. The attendant motion of arm 28 to the left lifts lever 20 against the action of the weights 23 which serve to tension the warp threads W. When the warp beam is free to turn and thus reduce the tension in the warp threads the weights 23 fall and act through lever 20 and links 30 and 31 to turn lever 25 in a right hand direction as viewed in Fig. 2 to move the arm 15 and whip

roll rearwardly. A corresponding rearward motion occurs at the opposite end of the whip roll, and the latter is therefore moved backwardly until mechanism to be described hereinafter clamps or locks the beam stationary, whereupon the operation is repeated.

The matter thus far described is of common construction and may be similar to that set forth in prior patents to Payne Nos. 2,103,821 and 2,184,059 to which reference may be had for a further understanding of the structures already set forth.

The warp beam which I employ has secured thereto a shell to have frictional contact with brake shoes mounted on a fixed support which also supports the hydraulic brake shoe controlling unit as shown more particularly in Figs. 6 and 9. Secured to and extending rearwardly from the loom frame is a bracket 40 provided with a bearing 41 through which extends the right end of the warp beam gudgeon or shaft 42 as seen in Fig. 7. A disk 43 bolted as at 44 to bracket 40 supports studs 45 connected by a link 46, as indicated in Figs. 6 and 7. As shown in Fig. 6 the right and left studs 45 which pass through link 46 have pivoted thereon brake shoes 47 and 48, respectively, which extend upwardly to a hydraulic brake operating unit 49. The latter is held as at 50 to the disk 43, see Figs. 6 and 7, and is connected to a hydraulic tube 51. The brake shoes are therefore supported on fixed structure as is also the unit 49 and these parts are held against rotation around shaft 42 as will be apparent in Figs. 3 and 7.

The barrel 55 of the warp beam is fastened to shaft 42 and has secured thereto a head 56 to which is secured a drum 57. A hub 58 keyed to shaft 42 lies to the right of web 59 of the drum, and the hub, web and head are bolted together as at 60 to turn with the warp beam. Rods 61 located in grooves 62 extending longitudinally along the periphery of the barrel 55 are secured to the head 56, and act with shaft 42 to cause the drum to rotate with the barrel 55. The drum is formed with an internal cylindrical surface 63 positioned for engagement with the external surfaces of the shoes 47 and 48. The drum rotates with the barrel to feed warp and can either slide along the brake shoes if the latter are spaced from surface 63 as shown in Fig. 6, or be held by the shoes if they are forced apart and against surface 63 by the unit 49. In the latter instance the beam will be locked or held in stationary position because of the support afforded the brake shoes by the bracket 40.

The unit 49 which is secured to the disk 43 and shown in Fig. 9 comprises a cylinder 65 having an inlet port 66 intermediate the ends thereof on opposite sides of which are located front and back pistons 67 and 68, respectively. Rubber cups 69 contact the internal bores of the cylinder and each piston is provided with a pressure plug 70 for engagement with the corresponding shoes 47 and 48. The ends of the cylinder may be closed by rubber boots 71, and a light compression spring 72 engages the cups 69 to hold them against their respective pistons. The fluid within the cylinder 65 is confined between the cups and when subjected to increased pressure tends to move the pistons apart to force the brake shoes against the cylindrical surface 63 of the drum 57. When pressure within the cylinder 65 falls the pressure exerted by the pistons slackens and in order to insure release of the shoes from the braking surface 63 I employ

a tension spring 73 between the shoes 47 and 48 tending to draw the latter away from surface 63, as shown in Fig. 6.

The pressure of fluid in the member 49 is controlled through tube 51 which leads to a cylinder mounted in the present instance in fixed position and having a plunger the position of which can be changed to vary the fluid pressure within the system. As shown in Figs. 3 and 8 the bracket 13 has secured thereto a small stand 75 on the upper end 76 of which is mounted the pressure unit 77. The latter has a fluid reservoir 78 on the upper part thereof communicating by means of a port 79 with a cylinder bore 80. A piston 82 slides in the bore 80 and is movable along the latter by a piston rod 83 the left end of which as seen in Fig. 2 is located for engagement with the arm 28. A by-pass port 85 leads from the reservoir to the bore 80 and a rubber cup 86 is normally located between the intake and by-pass ports, being held against the piston 82 by a compression spring 87. A stop 88 limits motion of the piston to the left as viewed in Fig. 8 and serves to locate the cup 86 with respect to the ports.

The right end of spring 87 bears against a disk-like structure 90 limited as to right hand motion by the end of the bore 80 and having mounted therein a valve 91 which when open by fluid pressure incident to motion of the piston 82 to the right, Fig. 8, leads to the fitting 92 the bore of which communicates with the hydraulic tube 51.

The relationship of the unit 49, tube 51 and cylinder 77 is such that when the rod 33 moves to the right as viewed in Figs. 2 and 8 fluid within that part of the bore lying to the right of the by-pass port will be placed under pressure and this pressure will be communicated through the tube 51 to the pistons 67 and 68. When the force acting on rod 33 is released or reduced, the spring 87 moves the piston to the left to effect a reduction of fluid pressure within the system and spring 73 draws the pistons 67 and 68 toward each other.

In operation, the weight 23 will act as already described to hold the arm 28 in a right hand position, Fig. 2, when the whip roll is in its rear-most position, thus causing arm 28 to exert a force on piston rod 83 to the right as viewed in Figs. 2 and 8 to produce a relatively high level of fluid pressure within the system and cause the brake shoes 67 and 68 to move against the drum 57 and hold the beam stationary. As warp is consumed the whip roll will move forwardly, thereby moving the arm 28 to the left or in a direction away from the piston rod 83, whereupon the spring 87 will act to reduce the fluid pressure within the system until a level is reached which permits the beam to turn with respect to the brake shoes. The tension spring 73 assists in a quick release of the brake shoes but is not essential. When the beam is released the tension in the warp rotates the beam to feed warp forwardly with a resultant drop in warp tension which permits the weight 23 to move the whip roll rearwardly until arm 28 again moves piston rod 83 to the right to reestablish beam holding pressures within the hydraulic system.

The back and forth reciprocation of the whip roll goes on throughout the weaving operation, the whip roll moving forwardly to a given point in its cycle at which fluid pressure drops sufficiently to release the beam, whereupon the whip roll is returned by the weight to a second given point in its rearward travel at which holding

pressures are again established. The drum surface 63 slides smoothly over the shoes 47 and 48 to avoid abrupt movements of the warp beam and in this way an even feeding action of the beam is attained.

From the foregoing it will be seen that I have provided a simple and efficient means for regulating the locking and releasing of the warp beam by means of a hydraulic system the fluid pressure of which rises and falls constantly during loom operation to lock and release the warp beam alternately. It will further be seen that the piston rod 83 is acted upon by means, such as the whip roll and arm 28, responsive to variations in tension in the warp and that increasing tension in the warp operates through the hydraulic system to unlock the beam. It will also be seen that the weight 23 serves not only to move the whip roll rearwardly when the warp is slackened but also supplies the force needed to establish beam holding pressures within the hydraulic system.

The brake unit 49, tube 51, and pressure unit 11 as shown in Figs. 8 and 9 of themselves form no part of my present invention and may be of any approved form. For a further understanding of these parts reference may be had to printed matter relating to hydraulic brake systems, such for instance as subject #2062 and 2140 shown in the catalogue of November 18, 1938, of the Ford Motor Company.

Having thus described my invention it will be seen that changes and modifications may be made therein by those skilled in the art without departing from the spirit and scope of the invention and I do not wish to be limited to the details herein disclosed, but what I claim is:

1. In a warp let-off mechanism for a loom having a rotatable warp beam, brake means for the beam movable either to holding position to prevent rotation of the beam or to releasing position to permit rotation of the beam, a hydraulic system connected to the brake means, mechanism acting normally on the system to cause the latter to move the brake means to beam holding position, and other means to transmit an opposing force to the mechanism derived from the warp as the tension of the latter increases during the weaving operation while the beam is prevented from rotating and cause the mechanism to effect a reduction of fluid pressure within the system to a level insufficient to cause the brake means to hold the beam from rotation.

2. In a warp let-off mechanism for a loom having a rotatable warp beam, brake means for the beam, a hydraulic system connected to the brake means to control the amount of braking force exerted by said brake means on the warp beam, controller means for the hydraulic system, means operated by a force derived from the warp as the tension in the latter increases during the weaving operation when the warp beam is prevented from the rotating to cause the controller means to effect a reduction of fluid pressure within the hydraulic system to a level which permits the warp beam to move relatively to the brake means, and other means operative due to slackening of the warp tension incident to rotation of the warp beam to cause the controller means to establish fluid pressure within the system sufficiently high to cause the brake means to prevent rotation of the warp beam.

3. In a warp let-off mechanism for a loom having a rotatable warp beam, means moved from holding to releasing position by a force derived from the warp as the tension thereof

increases during weaving, provided rotation of the beam is prevented, brake mechanism to control rotation of the beam, a hydraulic system controlling the brake mechanism and under control of said means, return mechanism for the means to move the latter from releasing to holding position when tension in the warp is reduced, the means when in holding position maintaining sufficient pressure within said system to cause the brake mechanism to prevent rotation of said beam, said means when moving to releasing position reducing the pressure within the system to a level insufficient to cause the brake mechanism to prevent rotation of the beam, whereupon the warp due to the tension thereof causes rotation of the beam to reduce the warp tension and the return mechanism moves the means to holding position to reestablish sufficient pressure in the system to prevent further rotation of the beam.

4. In a warp let-off mechanism for a loom having a rotatable warp beam, brake means for the beam movable either to beam holding or releasing position, a hydraulic system connected to and controlling the brake means, a whip roll movable forwardly to a given position during the weaving operation by a force derived from the warp when the warp beam is held against rotation, means tending normally to move the whip roll rearwardly to a second given position, and mechanism to vary the fluid pressure within the system, said mechanism being caused by a force derived from the whip roll when the latter moves forwardly to said first given position to produce a pressure within the system insufficient to cause the brake means to hold the warp beam, and said mechanism effective when the whip roll moves rearwardly to said second given position to produce sufficient pressure within the system to cause the brake means to hold the warp beam against rotation.

5. In a warp let-off mechanism for a loom having a rotatable warp beam and a whip roll movable forwardly by the warp during the weaving operation when the beam is prevented from rotating, the loom having return means to move the whip roll rearwardly due to lessening of the warp tension when the beam rotates to feed warp, brake means for the beam movable to holding position to prevent rotation of the beam, release means to move the brake means to releasing position to permit rotation of the beam by the warp, a member moved by the whip roll from holding to releasing position when the whip roll moves forwardly, said return means to move the member from releasing to holding position when the whip roll moves rearwardly, and a hydraulic system connected to the brake means and controlled by the member to have the pressure therein increased to move the brake means to holding position when the member moves to holding position, and have the pressure therein reduced when the member moves to releasing position, whereupon the release means moves the brake means to releasing position.

6. In a warp let-off mechanism for a loom having a rotatable warp beam and a whip roll movable forwardly by the warp during the weaving operation when the beam is prevented from rotating, the loom having return means to move the whip roll rearwardly due to lessening of the warp tension when the beam rotates to feed warp, brake means for the beam movable to holding position to prevent rotation of the beam, release means to move the brake means to releas-

ing position to permit rotation of the beam by the warp, and a hydraulic system connected to the brake means and controlled by the whip roll and said return means, the whip roll when moving forwardly operative to decrease the pressure within said system to permit the release means to move the brake means to releasing position, and said return means operative when the whip roll moves rearwardly to increase the pressure in said system to overpower said release means and move the brake means to holding position.

7. In a warp let-off mechanism for a loom having a rotatable warp beam, a whip roll for the warp movable backwardly and forwardly, means including a weighted lever tending normally to move the whip roll rearwardly, the warp due to increase in tension therein during the weaving operation moving the whip roll forwardly against the action of the weighted lever when the warp beam is held against rotation, brake means for the warp beam movable to holding and releasing positions with respect to the beam, a hydraulically operated unit for the brake means, a hydraulic cylinder having a plunger in position for operation by said weighted lever, and tubular means connecting the unit and cylinder, said unit, cylinder and tubular means constituting a hydraulic system, the lever when moving in a direction to move the whip roll rearwardly operating the plunger to increase the fluid pressure within the system and cause the unit to move the brake means to holding position with respect to the beam, and said weighted lever being moved in a direction away from the plunger by forward motion of the whip roll reducing the fluid pressure within the system, whereupon the beam rotates with respect to the brake means due to tension in the warp and said weighted lever moves the weighted lever rearwardly and causes the plunger to create sufficient fluid pressure within the system to move the brake means to beam holding position.

8. In a warp let-off mechanism for a loom having a rotatable warp beam, a whip roll over which the warp passes from the warp beam to the weaving point, the warp tending to move the whip roll forwardly during the weaving operation when the warp beam is prevented from rotating, a lever having two arms one of which is operatively related to the whip roll and movable therewith, a weight connected to the second arm of the lever, said weight tending normally to move the first arm in a direction to cause rearward motion of the whip roll, brake means for the warp beam movable to holding and releasing positions relatively to the beam, and a hydraulic system between said lever and the brake means including a unit to control the brake means, said system including a cylinder having a plunger to be moved by the weight acting on the lever in a

direction to increase the fluid pressure within the system when the first named arm moves in the direction corresponding to rearward motion of the whip roll to cause the unit to move the brake means to beam holding position, movement of the first named arm in a direction corresponding to forward motion of the whip roll moving the lever in a direction away from the plunger, whereupon fluid pressure within the system is decreased to permit turning of the beam relatively to the brake means, the weight being effective through the lever to move the whip roll rearwardly and reestablish sufficient fluid pressure within the system to cause the brake means to prevent rotation of the warp beam.

9. In a warp let-off mechanism for a loom having a rotatable warp beam, brake means for the beam, a hydraulic system connected to the brake means to control the amount of braking force exerted thereby on the warp beam, a whip roll moved forwardly by the warp during the weaving operation when the warp beam is prevented from turning, weighted means tending normally to move the whip roll rearwardly, a controller for the system to determine the fluid pressure within said system, controller actuator means by which the whip roll when moving forwardly causes the controller to reduce the fluid pressure within the system to a point which will permit the warp beam to turn with respect to the brake means, and the weighted means effective during rearward motion of the whip roll to move the actuator means to cause the controller to increase the fluid pressure of the system to a point which will cause the brake means to prevent rotation of the warp beam.

10. In a warp let-off mechanism for a loom having a rotatable warp beam, brake means for the beam, a hydraulic system connected to the brake means to control the amount of braking force exerted by said brake means on the warp beam, a controller for the hydraulic system movable in one direction to decrease and in the opposite direction to increase the fluid pressure within said system, controller actuator means to cause the whip roll when moving forwardly to move said controller in said one direction, means to move the whip roll rearwardly and move the actuator means to cause movement of the controller in said opposite direction, the increase in fluid pressure within the system being sufficient to cause the brake means to prevent rotation of the warp beam when the whip roll reaches a given point in its rearward motion, and the decrease in pressure within the fluid system reaching a level insufficient to enable the brake means to prevent beam rotation when the whip roll reaches a given position in its forward motion.

ARCHIBALD J. HERARD, JR.
